UNITED STATES PATENT OFFICE.

CLARK ROBINSON, OF HARTLEY, IOWA.

HEATING DEVICE FOR WAGON-TIRES AND STOVES.

SPECIFICATION forming part of Letters Patent No. 630,411, dated August 8, 1899.

Application filed May 4, 1899. Serial No. 715,556. (No model.)

To all whom it may concern:

Be it known that I, CLARK ROBINSON, a citizen of the United States of America, residing at Hartley, in the county of O'Brien and State of Iowa, have invented certain new and useful Improvements in Heating Devices for Wagon-Tires and Stoves; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to tire-heaters of that class using oil as fuel and burner and vaporizing pipes as means for consuming the oil.

The object of the invention is by a novel construction and arrangement of parts to materially reduce the cost of construction of a tire-heater of this character, while retaining its full effectiveness and increasing its rapidity and convenience in use.

The invention will be hereinafter fully described and claimed.

Referring to the drawings, in which the same numerals of reference indicate corresponding parts in the several views, Figure 1 is a perspective view of my new and improved tire-heater. Fig. 2 is a central vertical sectional view of the same. Fig. 3 is a sectional view through one of the supporting brackets.

The oil passes from an elevated reservoir 8 through the supply-pipe 2, the horizontal portion of which is arranged centrally within a cylinder or retort 1, and said portion within the retort is formed with a series of small apertures 2^a, through which the oil drops to the bottom of the retort or cylinder, the inner end of said supply-pipe 2 being closed by a cap. The ends of the retort or cylinder are also closed by caps, as shown.

The straight retort or cylinder 1 is connected centrally by a coupling 9 with a straight burner-pipe 3, extending in a line beneath the retort. This retort 1 and burner 3 together form a straight vaporizer. The ends 3^a of the burner-pipe extend upward at right angles and connect at their upper ends with the circular burner or tire-heating pipe 6, the

latter being thus raised above the plane of the burner-pipe 3. In some instances I may prefer to omit the circular burner-pipe 6. It 55 is also obvious that said burner-pipe 6 could be lowered to a position on a level with the burner-pipe 3.

55 indicate the supporting-brackets, which are formed with the upper retort-bearings 5^a, which receive the retort or cylinder, and with intermediate bearings 5^b, which receive the burner-pipe 3 to hold and support the latter in position below the retort, said brackets also having rectangular openings 5^c to receive and support the long shallow pan 4 in line below the burner-pipe 3. The object of this pan is to catch the drippings of oil from the burner-pipe 3, and by lighting the oil collected in this pan before turning on the flow 70 of oil from the reservoir 8 the retort or cylinder is made hot before the oil begins to flow into it from the reservoir, thus effecting a saving and causing the generator or retort to operate at once. The oil being then turned 75 on flows into the perforated supply-pipe 2 and drops through the perforations therein upon the hot bottom of the retort, when the vaporization at once begins. The vapor thus generated mixes with the requisite quantity 80 of air, which enters the retort through an opening 10 in one of its end caps, passes down through the central coupling 9 into the burner-pipe 3, and a portion of it burns at the flame-openings in the latter, while the bulk of the 85 vapor thus generated passes on into the circular burner-pipe 6, over which the tires are suspended, entering the said circular burner-pipe from both ends of the burner-pipe 3. It will be noted that the supply-pipe 2 passes 90 through the opening 10, and therefore said opening is a little larger than the pipe to permit a certain quantity of air to pass into the retort.

By elevating the circular burner-pipe 6 95 above the burner-pipe 3, as shown, no oil can get into said circular pipe. Therefore when the oil in the burner-pipe 3 begins to generate it forces the gas or vapor to rise into the circular burner-pipe 6, where it burns. 100

It will be seen that by placing the retort across the circle of the tire-heating pipe 6, instead of forming it in a circle or square, I save almost one-half the cost of making the

- heater, while by using the burner 3 to heat the retort before the vapor reaches the burner 6 I save the amount of oil it would take to fill the pipes in the old way.
- 5 A suitable cover—such as described in my prior patent, No. 527,541, dated October 16, 1894—may be employed, and the heater may be set directly upon the ground or upon a suitable base.
- 10 By omitting the circular burner-pipe the straight vaporizer, consisting of the retort and burner-pipe 3, with the supporting-brackets and drip-pan, could be used as a heating device for stoves or other purposes.
- 15 Having thus described my invention, what I claim, and desire to secure by Letters Patent, is—
1. A tire - heater, comprising a circular burner, a straight retort extending across the circle of said burner and means for supplying oil and air to said retort, and the straight burner extending in line beneath and communicating with the retort and also with the circular burner, and arranged below the plane of said circular burner, substantially as and for the purpose set forth.
2. A tire - heater, comprising a circular burner, a straight retort extending across the circle of said burner, and means for supplying oil and air to said retort, the straight burner extending in line beneath the straight retort below the plane of the circular burner, communicating centrally with the retort and having the upwardly-extending ends commu-

nicating with the circular burner, substantially as set forth.

3. A tire - heater, comprising a circular burner, a straight retort extending across the circle of said burner, and means for supplying air and oil to said retort, the straight burner extending in line beneath and communicating with the retort, and also with the circular burner, and arranged below the plane of said circular burner, and the long drip-pan positioned in line beneath the straight burner, for the purpose specified; substantially as set forth.

4. The herein-described tire-heater, consisting of the circular burner, the straight retort extending across the circle of the same, the supply-pipe leading from a suitable reservoir and extending inside the retort and formed therein with the small feed-openings; the straight burner-pipe extending in line beneath the straight retort, below the plane of the circular burner, communicating centrally with the retort and having the upwardly-extending ends communicating with the circular burner, and the drip-pan mounted in line beneath the straight burner-pipe, for the purpose specified; substantially as set forth.

In testimony whereof I affix my signature in presence of two witnesses.

CLARK ROBINSON.
